UNITED STATES PATENT OFFICE

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS

WARPING APPARATUS

Application filed March 25, 1933. Serial No. 349,846.

This invention relates to creels for supporting supply yarn masses, as, for example, warper creels, and more particularly to creels in which the yarn masses are non-rotatably supported for the drawing of yarn off the ends of the yarn masses. In creels of the last-mentioned type, it is necessary to provide means to prevent the yarn or thread from kinking when the warper stops, as the 5 yarn unwinds so freely from such yarn masses that kinks formed at the time of stopping will not be straightened out when the warper is again set in operation. Moreover, it is necessary to keep the yarn under tension while the warper is idle, in order to prevent tangling. In a certain prior-art warper to which yarn is supplied from cross-wound conical yarn masses non-rotatably mounted, there is a tension device adjacent to 10 each cone which acts upon the thread at all times. This tension device is effective to insure that kinks shall be straightened out upon restarting of the warper, and to prevent tangling of the yarn while the warper 15 is at rest, but inasmuch as the tension device acts at all times it limits the speed at which the warper may be operated.

The object of the present invention is to provide a tension device which shall act only 20 when needed, namely, while the warper is idle and while it is being started, and which consequently places no tension upon the yarn in normal operation of the machine, and therefore does not limit the warping speed.

In the prior-art warper just referred to it is impracticable to make the tension devices uniform in their action, hence they place a varying amount of tension upon the yarn being warped. Since the tension devices of 35 the creel herein disclosed do not act during the normal operation of the warper, there is uniformity of tension of the yarn being warped. There is also less yarn breakage, as the yarn is under very light tension.

In the accompanying drawings,

Figure 1 is a fragmental side elevation of a creel provided with tensioning devices embodying the features of my invention, the creel being shown in operative relation to a 50 warper.

Fig. 2 is a fragmental plan view of the creel.

Fig. 3 is a plan view of one of the tension devices and its operating mechanism.

Fig. 4 is a front elevation of the parts 55 shown in Fig. 3, the tension device being illustrated in its ineffective position.

Fig. 5 is a right-hand side elevation of said parts, the tension device being shown in its operative position.

Fig. 6 is a fragmental sectional view of the tension device in its operative position.

The embodiment herein shown of the invention comprises a warper A and a creel B. In the present instance I have shown a beam 65 warper, but it will be understood that the invention is applicable as well to a ball warper. For a more detailed description of the warper herein illustrated, reference may be made to the Melchor Patent No. 1,683,367, dated September 4, 1928.

While the creel B may partake of various forms, it is herein shown as comprising two upright frames 1 and 2 which are adjacent each other at one end and separated from 75 each other at the opposite end so as to constitute a V-shaped structure, the frames 1 and 2 being rigidly connected together at their adjacent ends. So far as the present invention is concerned, the particular form of 80 the yarn masses is not important. Herein are shown conical cross-wound yarn masses b. The means for supporting the yarn masses may be of any preferred construction, as, for example, arms 2a, such as those disclosed in 85 the De Wolf Patent No. 1,660,299, dated February 21, 1928. As shown in Fig. 2 herein, the yarn masses are arranged in pairs, and the pairs are arranged in tiers or columns.

In the present construction, the creel 90 frames 1 and 2 comprise vertical rods 3 on which are supported the devices for guiding the yarn in its course from the cheeses to the warper and for applying tension to the 95 yarn upon the stoppage of the warper. Each rod 3 carries a vertical series of yarn-guiding and tensioning means. The yarn-guiding and tensioning means for each pair of yarn masses comprises a bracket 4 attached to the rod 3, said bracket carrying yarn guides 100

and 6. Intermediate the yarn guides 5 and 6 is a tension device comprising two horizontally-disposed disks 7 and 8, the disk 7 being fixed to the bracket 4 and the disk 8 being axially alined with and overlying the disk 7. A plunger 9 is guided for vertical movement in an opening 10 in the bracket 4 and a central opening 11 in the disk 7. Downward movement of the plunger is limited by engagement of the annular shoulder 12 on said plunger with the bracket 4. The upper portion of the plunger 9 is reduced in diameter and extends slidably through a central opening 13 in the disk 8. The reduction in diameter of the plunger 9 provides an annular shoulder 14 which lies within the central recess 15 in the lower side of the disk 8.

When the plunger 9 is in its lowermost position, as shown in Fig. 6, the disk 8 rests upon the disk 7 or upon a thread extending from the guide 5 to the guide 6, the thread having arcuate contact with the plunger 9, as indicated in Fig. 3. In the present construction gravity is depended upon to move the plungers 9 and the tension disks 8 into their lower positions, but if desired, other means may be employed. It will be seen that upward movement of the plunger 9 will bring the shoulder 14 into engagement with the end wall of the recess 15 and thus lift the disk 8, thereby freeing the thread from the pressure of said disk.

The means for raising each vertical series of plungers 9 comprises a vertical rod 16 guided at its ends for longitudinal movement. Fixed to the rod 16 are arms 17, one for each of the plungers 9. While caction between the plungers 9 and the arms 17 may be effected in various ways, I have herein shown each arm as underlying its respective plunger and as being normally a slight distance below it so that the annular shoulder 12 of the plunger may rest upon the bracket 4. The means for raising and lowering the rod 16 may be of any preferred construction, that herein shown comprising a rock shaft 18 journaled in the lower portion of the creel frame and having fixed thereto as many arms 19 as there are rods 16. The means herein disclosed for connecting each arm 19 to the adjacent rod 16 comprises a fork 20 on the end of the arm, said fork embracing the rod and having slots 21 to receive the ends of a pin 22 extending through the rod.

The two rock shafts 18 are herein shown as connected for simultaneous oscillation by means of a rock shaft 23 (Fig. 2) carrying gear elements 24 that mesh with corresponding gear elements 25 on the shafts 18. The shaft 23 is connected to the starting and stopping mechanism of the warper so as to cause the tension disks 8 to be lifted into inoperative position when the warper is thrown into high speed and so as instantly to lower the

tension disks 8 into yarn-tensioning position when the warper is stopped.

In the warper selected for illustration herein, 26 is a treadle arranged to swing upon the axis of a shaft 27, said treadle being connected to operate the belt shifter 28. 29 is the drive belt. Rigid with the treadle 26 is a crank arm 30 which is connected through a link 31 to a crank arm 32 on the shaft 23. The weight of the rods 16 and connected parts tends to lift the treadle 26 and shift the drive belt 29 onto the loose pulley. The means for holding the treadle down in the high-speed position shown in Fig. 1 is controlled by the detectors or drop wires 34, but has not been illustrated, as it may be of the ordinary or any preferred character.

In operation, when a thread breaks the treadle is released, whereupon the weight of the rods 16 and connected parts causes the shaft 27 to turn in the direction to shift the drive belt 29 onto the loose pulley and to turn the shafts 18 in the direction to permit the tension disks 8 to drop into contact with the threads, the warper brake (not shown) being actuated at the same time to stop the warper promptly. The operator then draws forward to the warper the broken end attached to the supply yarn mass. The operator finds the thread end on the beam, to facilitate which the operator may set the beam in slow rotation by partially depressing the treadle, as described in said Melchor patent. The clearances between the arms 17 and the lower ends of the plungers 9 and the distance between the shoulders 14 on said plungers and the end wall of the recesses 15 are such that the warper may be placed in low speed without lifting the tension disks 8 into inoperative position. It will be seen that while the warper is standing idle and while it is being prepared for high-speed operation, the tension devices act to keep the yarn from becoming tangled. When the warper is being placed in high speed the tension disks 7 remain in tensioning position only long enough to straighten out any kinks there may be in the yarn.

It will be evident that since the tension devices are in use only when needed, namely, while the warper is idle and while it is being started, there is less yarn breakage, consequently a much higher speed may be attained than has heretofore been practicable.

I claim as my invention:

1. The combination with a creel comprising a plurality of yarn mass supports, a corresponding plurality of individual yarn tensioning devices, and a vertically movable rod arranged to render said tensioning devices inoperative, of a warper having means for placing the warper in and out of operation, said means including a treadle, and connections between the treadle and said rod for raising and lowering the latter to throw the

tensioning devices into and out of operation.

2. The combination with a creel comprising a plurality of yarn mass supports and a corresponding plurality of individual yarn tensioning devices, of a warper having means for placing the warper in and out of operation, said means including a treadle, and connections between the treadle and the tensioning devices for throwing the latter into and out of operation.

3. In a creel, the combination of a plurality of yarn mass supports, a corresponding plurality of yarn tensioning devices, each of said devices comprising two horizontally disposed disks between which a thread may run, a plunger supported for vertical movement axially of said disks, said plunger being arranged to engage and lift the upper disk to render the tensioning device inoperative, a vertically movable rod having a plurality of arms, each arm underlying one of said plungers, and means for raising and lowering said rod to throw the tensioning devices into and out of operation.

4. In a warping apparatus, the combination of a plurality of yarn mass supports, a corresponding plurality of yarn tensioning devices, each of said devices comprising two disks between which a thread may run, a warper, and means controlled by the warper for simultaneously separating the disks of said tensioning devices to render said devices inoperative.

5. A yarn-guiding and tensioning device comprising a bracket having an opening therethrough, a plunger vertically movable in said opening and having a shoulder to rest on the bracket, and two horizontally-disposed disks between which a thread may run, said disks having central openings through which said plunger extends, the lower disk resting upon said bracket, said plunger having a shoulder to engage and lift the upper disk upon upward movement of the plunger, said upper disk being recessed to provide clearance between the last mentioned shoulder and the upper disk.

In testimony whereof, I have hereunto affixed my signature.

BURT A. PETERSON.
